GOLF CLUB

Milton B. Reach, Springfield, Mass.

Application June 26, 1957, Serial No. 668,121

2 Claims. (Cl. 273—164)

This invention relates to a golf club and more particularly to an improved golf club head of the wood play type.

Preliminary to a golf club stroke, the club head is placed behind the ball, the feet are positioned, and the eyes of the player survey the approach to the target. The eyes are then transferred to the head of the club while the mind pictures the mechanics of the swing. It is in this stage of the preliminaries that confidence as to the successful execution of the stroke comes into play. As the swing starts, the eyes, as a rule, concentrate on the back of the ball, and the player's head is held steady until impact. The smoothness of the swing reflects the degree of confidence had by the player in the preliminaries. It is noteworthy that the more expert player can confidently propel the ball from a normal fairway lie, using a driver for the shot, because he knows that the speed of the club head and the ball marking automatically create the desired flight. The average player, on the other hand, needs the assurance of the dominant face loft of a spoon to promote the desired confidence. The tendency of the average player is to err on the side of maximum loft. This produces increased height, more wind difficulty, and loss of distance.

The conventional spoon employed in such golf shots has a distinctly convex upper surface, and the eyes of the player, looking down on such a club head, are led groundward by the head curvatures, the impression being much the same as looking down on the back of a turtle. Moreover, the portion of the club head closest to the player's eye, and hence the most prominent portion, is not in the plane of the desired point of impact (the sweet spot) on the face of the club but instead is nearer the center of the club head, the region of highest elevation. Using such a club, the average player tends to duck the right shoulder in an effort to produce an upward trajectory of the ball. In so doing, the ball is given too much lift, and an improper shot results. In short, the conventional spoon does not provide the confidence necessary in the shot, and the long flying spoon shot to the distant target, which is one of golf's greatest thrills, is frequently missed.

The club head of the present invention overcomes the deficiencies inherent in conventional wood play club heads, and with the foregoing facts in view it is a principal object of the invention to provide such an improved golf club.

A further object of the invention is to provide a club head of the wood play type which gives an impression of lift and which, therefore, instills confidence and prevents the overcompensation frequently made by the average player.

An additional object of the invention is to provide a club head of the wood play type which directs the eye of the player to the desired point of impact, or sweet spot, and which makes the location of this point most prominent to the eye of the player.

Another object of the invention is to provide a golf club head of the wood play type which has a more favorable distribution of weight than has heretofore been possible.

2

Briefly stated, the objects of the invention are accomplished by providing a club head of the wood play type having front face, back, top, bottom, and side surfaces, the top surface having its greatest elevation above the bottom surface at its junction with the front face and sloping rearwardly therefrom toward the bottom surface. The principal surfaces of the club head have an acute angular relationship, and the top surface of the head is concave, with the concavity centered about the geometric center of the top surface. The junction of the top surface with the front face then becomes the region nearest to the eye of the player and hence the most prominent region, and the effect is enhanced by converging markings on the top surface of the head which guide the eye of the player directly to the desired impact region. By virtue of the concavity of the top surface of the club head, the center of mass of the head is lowered, and the total mass reduced, so that additional weights may be applied to the lower portions of the club head to make the weight equal to that of a conventional head of the same number and at the same time to lower the center of mass even further.

The foregoing and other objects of the invention and the exact manner in which such objects are accomplished will become more readily apparent upon consideration of the following detailed description of the invention when taken in conjunction with the accompanying drawings which illustrate a preferred embodiment of the invention and wherein:

30 Figure 1 is a perspective view of the club head of the invention;

Figure 2 is a top plan view of the head of Figure 1; Figure 3 is a front-to-back vertical sectional view taken along line 3—3 of Figure 2 in the direction of the arrows; and

35 Figure 4 is a side-to-side vertical sectional view taken along line 4—4 in the direction of the arrows.

Referring to the drawings, the club head 10 of the invention has a toe 12, a heel or hosel end 14 (which is attached to a conventional shaft), a front face 16, a rear surface 18, a top surface 20, and a bottom or sole surface 22. The principal surfaces of the club head are the front face 16, the top 20, and the bottom 22. The bottom surface 22 is preferably slightly cylindrically convex so that its front-to-back center line is substantially flat as shown in Figure 3, and its side-to-side center line is curved as shown in Figure 4.

As shown in Figure 3, if the club head is placed on a level surface, a line A perpendicular to the bottom surface 22 at its geometric center will be substantially vertical. The top surface of the club head slopes rearwardly from its region of greatest elevation at the junction with the front face 16, downwardly toward the bottom surface 22. The front face 16 meets the bottom 22 at an acute angle. The top surface 20 meets the front face 16 at an angle of not more than 90°, so that this angle may also be considered acute. A rearward projection of the top surface beyond the rear surface 18 would meet a similar rearward projection of the bottom surface 22 at an acute angle. Thus, the three principal surfaces of the club head have an acute angular relationship.

Again referring to Figures 3 and 4, the top surface 20 of the club head is made dished or concave, with the concavity generally spherical and centered on the geometric center of the top surface and over the center of the head mass. With the club head in the normal position of Figure 3, a line B drawn perpendicular to the top surface 20 at the geometric center of the surface would have a rearward slope as shown. If the club head were tilted so that the line B became vertical, a plane containing the peripheral edges of the top surface would then be substantially horizontal. From its maximum elevation

at the periphery, the top surface would extend downwardly toward the geometric center in slopes of varying pitch. With the club held in its normal position, if lines were drawn perpendicular to the elemental slopes, such lines would intersect an imaginary axis from the club head to the player's eyes at different heights and at different angles.

The net result of the foregoing head configuration is that when the club is held behind the ball during the preliminaries to a golf stroke, the eye is directed to the nearest region of the club head, which is the junction of the top surface with the front face, and the continuous upward slope of the top surface toward this junction together with the concavity of the top surface create an impression of lift which has been found in practice to instill the necessary confidence in the player and eliminate the usual tendency to duck the right shoulder and produce too much lift. In fact, with a club head of the type described, the angle of loft of the front face may be substantially reduced from the angle of comparable conventional clubs.

The foregoing effect is enhanced by providing markings 28 on the upper surface of the club head which converge toward the location of the point of impact or sweet spot and which direct the eyes of the player to this point. The sweet spot may be located at approximately the center of an insert 24 on the front face of the club. This insert may be L-shaped as shown in Figure 3 and may be attached to the club head by suitable screws 26. Inserts of metal, fiber, or other materials may be employed, as is well known. The markings have also been found to emphasize the impression of lift and may contrast in color with the remainder of the top surface.

By virtue of the elimination of the club head material normally present in the convex curvatures of the conventional club heads, the weight of the club head of the invention is substantially reduced, the configuration of the invention reducing the weight of an equivalent wood play head by about three quarters of an ounce. Such weight reduction at the same time lowers the center of mass of the head, which has a beneficial effect on the swing, and the effect may be further accentuated by adding weights to the lower regions of the club head, such weights making the total weight of the club head the same as comparable conventional club heads but lowering the center of mass substantially. Reference numeral 30 designates a typical weight which may be added. If such weights are metal, they may be secured to the club head by suitable screws, but it is preferred to employ weights of the type described in my co-pending application Serial No. 541,615 filed October 20, 1955. These

weights comprise comminuted litharge or similar material distributed in a rubber matrix and may be bonded or otherwise attached to the club head. The dish top construction of the invention also permits the use of plastics of higher specific gravity than wood in manufacturing the club head and yet retains the desirable deep striking face of the club head to accommodate the wide flattening of the ball under impact and prevent a well hit ball from riding over the top of the club and lose distance in so doing.

From the foregoing description of the invention it will be apparent that a golf club having unique characteristics is provided. While a preferred embodiment of the invention has been shown and described, it will be apparent to those skilled in the art that changes may be made without departing from the principles and spirit of the invention, the scope of which is defined in the appended claims. Accordingly, the foregoing embodiment is to be considered illustrative rather than restrictive of the invention, and those modifications which come within the meaning and range of equivalency of the claims are included therein.

1. claim:

1. In a golf club, a head of the wood play type having a substantially flat bottom surface substantially perpendicular to the vertical axis of the head, a front face, and a top surface which slopes continuously downwardly and rearwardly from said front face such that a projection of the top surface beyond the back of the head would meet a similar projection of the bottom surface in an acute angle, said top surface being slightly concave in its front-to-back and heel-to-toe cross-sections, the top surface having varying elemental slopes between its periphery and central region, whereby lines projecting perpendicularly from said slopes would intersect an axis from said head to the eyes of the user of the club at different heights, creating an impression of uplifting flight of the ball and adding confidence to the swing of the user.

2. The club of claim 1, further comprising markings on said top surface which converge toward the point of impact on said front face.
